Primary Examiner — Wan Laymon*Assistant Examiner* — Mark Booker(74) *Attorney, Agent, or Firm* — Bradley Arant Boult Cummings LLP(57) **CLAIM**

The ornamental design for an intradiscal shim, substantially as shown and described.

DESCRIPTION

FIG. 1 is a perspective view of a front side of an intradiscal shim showing our new design;

FIG. 2 is a perspective view of a rear side thereof; and,
FIG. 3 is a side view thereof.

The broken lines shown in the figures are included for the purpose of illustrating portions of the article and form no part of the claimed design.
